UNITED STATES PATENT OFFICE

GEORGE W. WINDSOR, OF SACRAMENTO, CALIFORNIA, ASSIGNOR OF ONE-THIRD TO
ALBERT E. GRIMM, OF SACRAMENTO, CALIFORNIA

VERTICAL-LIFT AIRPLANE

Application filed February 25, 1929. Serial No. 342,531.

This invention relates to airplanes, my principal object being to provide an airplane with an arrangement of propellers so placed that the plane may lift straight from the ground without having to make a long run into the wind as is now the case. Conversely the plane may descend straight down instead of having to glide or come at a gradual angle. This feature also enables the plane to remain practically stationary in the air without having to continually advance in order to keep from falling, as is at present the case. At the same time the lifting propellers are so placed as to offer no resistance to the forward travel of the machine.

A further object of the invention is to provide means for operating the lifting propellers so that their efficiency may be varied, thus enabling these propellers to function to keep the plane on a level keel or properly banked as may be desired.

Still another object is to mount the wing propellers so that they may be turned from lifting to forward propelling positions at the option of the pilot, so as to aid in driving the plane forward when it has been raised to the desired elevation, and a flying speed has been attained.

These objects I accomplish by means of such structure and relative arrangement of parts as will fully appear by a perusal of the following specification and claims.

In the drawings similar characters of reference indicate corresponding parts in the several views:

Figs. 1 and 2 are fanciful perspective views of a monoplane in flight, equipped with my special propeller arrangement and showing the propellers in lifting and forward propelling positions respectively.

Fig. 3 is a fragmentary longitudinal section of a monoplane showing the driving mechanism of the different propellers, somewhat diagrammatically.

Fig. 4 is a top plan view of a wing mounted propeller in its forward propelling position and partly in section.

Fig. 5 is an enlarged transverse view of the wing propeller control mechanism.

Fig. 6 is an enlarged longitudinal frag-

mentary view of said mechanism showing the control structure for the rear or fuselage lifting propeller.

Fig. 7 is a fragmentary cross section on the line 7—7 of Fig. 6.

Fig. 8 is a fragmentary plan section of a hand actuated control mechanism taken on the line 8—8 of Fig. 5.

Fig. 9 is a fragmentary enlarged plan section of a wing propeller having adjustable blades.

Fig. 10 is a fragmentary section on the line 10—10 of Fig. 9.

Referring now more particularly to the characters of reference on the drawings, and particularly at present to Figs. 1 to 8, 1 denotes the fuselage of a monoplane having the usual single wing 2 extending across the top of the same. Relatively large circular openings 3 are cut through the wing at equal distances to the side of said fuselage and a similar opening 4 is cut through the fuselage a predetermined distance rearwardly of the wing. Propellers 5 are mounted in the openings 3 and a propeller 6 in the opening 4. The propeller 6 is preferably mounted so as to be permanently disposed in a horizontal plane between the top and bottom surfaces of the fuselage, but the propellers 5 are mounted so as to be either in horizontal planes between the top and bottom surfaces of the wing or disposed in a vertical plane so as to project both above and below the wing. This special mounting of the wing propellers will now be described and since each mounting is a duplicate of the other only one will be taken into consideration in this description.

Each propeller is mounted in a yoke-like frame 7 whose sides are substantially parallel to the longitudinal plane of the blades and are disposed in a transverse plane relative to the fuselage or longitudinally of the wing. At its ends this frame is turnable in bearings 8 secured to the wing frames 9 in any suitable manner. The axis of rotation of the frame is the same as that of the drive shaft 10 of the propeller which projects through said frame from the end nearest to the fuselage to a bevel gear 11, which meshes with a similar gear 12 mounted in connection with the propeller.

axially thereof. It will therefore be seen that the frame and the propeller may be swung from a horizontal to a vertical position without interfering with the driving of the propeller. The frame may be thus swung or held at any position by suitable means such as sprocket wheels 13 fixed on the frame 7 at its ends and concentric with its axis and connected by chains 14 to similar sprockets mounted on a horizontal shaft 15 extending along the wing beyond the opening 3. This shaft extends to an operating mechanism 16 of suitable type disposed in the fuselage in a position convenient to the pilot.

15 The speed and consequently the efficiency of the propellers in either position is controlled as follows:

16 The shafts 10 of the two propellers project into the fuselage and terminate in splined portions 10a on which friction discs 17 are slidable. These discs engage a friction drive disc 18 mounted in a supporting structure 19, and which is driven, through the medium of bevel gearing 20 and other driving elements indicated conventionally at 20a, from the usual engine 21 of the airplane. This engine also drives the main driving propeller 22 positioned as usual in the nose of the machine.

30 A clutch 23 is disposed between the propeller 22 and the engine and is controlled by a hand lever 24 or the like convenient to the pilot. A similar clutch 25 likewise controlled by a lever 26 is disposed between the engine 35 and the disc driving mechanism. Either the front propeller or the other propellers may be cut out as may be desired or they may be all operated simultaneously, according to the conditions under which the airplane is being operated.

40 The discs 17 of the side propellers are disposed in opposed relation to each other and engage the disc 18 in common, as shown in Fig. 5. They are controlled so as to be shifted to or from the center of the driving disc respectively, or both moved toward or from the center of said disc at the same time, at the option of the pilot, by the following means:

50 Mounted in connection with the discs 17 are shifting forks 27 which at their outer ends are rigidly connected to separate sleeves 28 which are slidable in bearings 29 formed on the supporting structure 19 and parallel to the shafts 10. A vertical control lever 30 disposed between said sleeves is mounted at one end for universal swinging movement in a fixed support 31, and intermediate its ends has slidable but non-turnable engagement with a horizontal disc or similar member 32. 55 This disc in turn is slidable longitudinally of the airplane in a guide yoke 33 which extends horizontally at right angles to the sleeves, and is slidably supported therefrom by side trunnions or rods 34 thereon which 60 have sliding but non-turning engagement

with the adjacent ends of the sleeves 28. Links 35 or similar connection members extend from the disc 32 in diametrically opposed positions thereon to the adjacent ends of the sleeves. By means of this arrangement it will be seen that if the lever is shifted transversely of the airplane while being held from turning, the sleeves will be moved in a common direction, or so that one disc 17 will move away from the center of the driving 75 disc while the other will move closer.

As a result of this operation one propeller may be speeded up while the other is slowed down. This in turn causes the fastest propeller to exert a greater efficiency than the other, resulting in a greater lifting effect being imparted to the wing on one side than on the other and taking the place of the usual ailerons, as will be evident.

If, however, the lever is held against 85 swinging but is rotated so as to rotate the disc 32, the sleeves 28 will move in opposite directions relative to each other and both discs 17 will be moved toward or away from the center of the driving disc. The speed 90 of both propellers will then both be increased or reduced simultaneously without altering the speed of the engine.

The same lever is utilized to alter the speed of the back or fuselage propeller as 95 follows:

The driving shaft 36 of the rear propeller (corresponding to the shafts 10) has a friction disc 37 splined on its forward end which engages the driving disc 18 rearwardly of and at right angles to the discs 17. The shifting fork 38 applied to this disc is rigidly connected to a rod 39 which is parallel to the shaft 36 and is slidably mounted in a bearing 40 on the supporting structure 19 (see Fig. 6). The forward end of this rod has a slotted yoke 41 through which the lever 30 slidably passes, the major axis of the yoke slot extending in a direction at right angles to the rod 39 or to the major axis of the yoke 33. The slotted guides 33 and 41 being relatively opposed to each other enables the lever to be swung to shift the side discs without affecting the rear disc or vice versa; or both sets of discs may be shifted simultaneously by swinging the lever diagonally.

The shaft 36 at its end adjacent the disc 37 is preferably mounted in bearings 42 which are fixed in a sleeve 43 whose outer surface is eccentric relative to the shaft and is turnable in a bearing 44 provided with the structure 19. The sleeve 43 is provided with a radial operating arm 45, and it will be seen that by rotating the sleeve one way or the other the shaft 36 will be raised or lowered and the disc 37 accordingly engaged with or disengaged from the driving disc 18. The vertical movement of the shaft to disengage the disc is so slight that it would not un-

duly strain the shaft even if the opposite end were rigidly mounted, nor would it affect the shifting mechanism. By this means, however, the rear propeller may be held stationary when desired without affecting the continued operation of the other propellers.

The provision of the engine clutches enables either set of propellers to be disengaged from the engine whenever desired, and also enables the load on the lifting propellers to be released if necessary when shifting the discs 17 and thus facilitating such movement. In order to maintain the driving disc constantly and equally engaging the driven discs, regardless of wear, said driving disc is splined on its axial driven shaft 46 and is yieldably pressed against the driven discs by a spring 47 disposed between the structure 19 and said disc 18.

Referring now to Figs. 9 and 10 the same result as to the efficiency of the propellers may be obtained by making the lifting propellers with adjustable blades instead of by altering their speed.

In this case the friction disc drive arrangement may be maintained if desired, but it may also be eliminated and a simpler constant-speed driving connection between the engine and each propeller may be used, as may be obvious.

In this construction the propeller supporting frame 7a is turnably mounted in the wing opening as before. The bevel gear 48 on the end of the drive shaft meshes with a gear 49 which is rigid with a hollow hub 50 from which the propeller blades 51 project outwardly. The blades at their hub ends are provided with spindles 52 extending lengthwise of the blades and turnably mounted in the hub, so that on turning the spindles the pitch of the blades may be altered so that the efficiency thereof may be decreased from a predetermined maximum to zero. The spindles may be thus turned without affecting the swinging of the frame 7a on its trunnions by suitable means such as follows:

A hollow shaft 53 rigid with the gear 49 projects through the hub and has a slide block 54 disposed thereabout inside the hub. Links 55 are connected at one end to and project from the block parallel to the shaft and are connected at the other end to radial and oppositely disposed arms 56 which are connected to the adjacent ends of the spindle 52. Sliding of the block 54 lengthwise of the shaft will therefore cause the blades to be turned in opposite directions, and since the pitch of the blades is of course opposite to each other such movement will cause the pitch of both blades to be altered simultaneously and to the same extent.

To thus manipulate said block a stem 57 is slidable through the shaft and is connected at one end to said block. At its other end

the stem projects clear of the shaft and past the axial line of the gear 48 and frame 7a and is connected to a shifting fork preferably in the form of a bellcrank 58 pivoted on the frame 7a. One arm of this bellcrank 70 engages the stem without interfering with its turning while the other arm terminates in the plane of the axial line of the frame 7a. From this arm a rod 59 projects axially through the frame 7a to one end of the same 75 where it is connected with a shifting mechanism 60 arranged to shift said rod lengthwise.

From the shifting mechanisms of both wing propellers connections would extend to 80 a suitable control mechanism at the fuselage, which, as will be obvious, may be substantially the same as that employed in connection with the shifting of the slide discs as described in connection with the first type of apparatus. The adjustable blade arrangement, as will be obvious, enables the efficiency of the propellers to be altered the same as by altering their speed and the same results in the control of the mechanism may be obtained.

If, in addition, the sliding disc type of drive is maintained an extremely efficient control of the machine as a whole may be obtained, as will be evident.

It is to be understood that ball or similar antifriction bearings of suitable character for the purpose are preferably used for all the constantly driven shafts.

Since of course the particular shape and construction of various frames, housings and other parts may be varied considerably according to individual conditions and the designer's preference, no detailed description of such parts has here been given.

It may also be noted that when arranging the structure in a biplane the lifting propellers would be placed in the lower wing. Consequently the driving disc mechanism in that case would be inverted from what has here been shown, since it would naturally be near the floor of the fuselage rather than adjacent the ceiling.

From the foregoing description it will be readily seen that I have produced such a 115 device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In an airplane, having openings through a wing thereof to the sides of the fuselage, and a similar opening through the fuselage rearwardly of said wing; propellers mount-

- ed within said openings on vertical axes, a common drive means for all said propellers, and a common means for altering the effectiveness of side propellers relative to the rear 5 propeller independently or simultaneously, selectively, without altering the speed of the drive means.
2. In an airplane, having openings through a wing thereof to the sides of the fuselage, 10 and a similar opening through the fuselage rearwardly of said wing; propellers mounted within said openings on normally vertical axes, and means for shifting the wing propellers to a horizontal axial position without 15 interfering with the operation thereof and means for rendering the rear fuselage propeller inactive when the wing propellers are thus disposed.
3. In an airplane, propellers mounted in 20 connection with a wing of the airplane to the sides of the fuselage, and another propeller mounted in connection with the fuselage rearwardly of the wing, a common drive means for all said propellers, and means including 25 a single lever for enabling the effectiveness of the side propellers relative to the rear propeller to be independently or simultaneously altered selectively.
4. In an airplane having a circular opening 30 through a wing to one side of the fuselage, a frame extending across the opening transversely of the airplane and pivoted at its ends in connection with the wing, a propeller mounted in the frame on an axis at right 35 angles to the pivotal axis of said frame, drive means for the propeller including a shaft extending partially through the frame axially of the pivotal connection thereof, and means for turning the frame about its axis.
- 40 5. In an airplane, a friction drive disc, a propeller, a shaft extending from said propeller at right angles to the axis of said disc, a driven friction disc slidably keyed on the shaft and normally engaging the drive 45 disc, means for sliding said driven disc, and independent means for moving said disc at right angles to the surface of the drive disc to disengage the driven disc from the driving disc.
- 50 6. In an airplane, a friction drive disc, a pair of propellers mounted in connection with a wing of the airplane, drive means for said propellers including opposed separate and longitudinally aligned shafts projecting to- 55 ward the disc at right angles to the axis thereof, driven friction discs slidably keyed onto said shafts and engaging said drive disc, and means for sliding said driven discs radially of the drive disc either in opposite direc- 60 tions or in the same direction selectively.
7. In an airplane, a friction drive disc, a pair of propellers mounted in connection with a wing of the airplane, drive means for said propellers including opposed separate and longitudinally aligned shafts projecting to- 65
- ward the disc at right angles to the axis thereof, driven friction discs slidably keyed onto said shafts and engaging said drive disc, shifting forks applied to said driven discs, longitudinally aligned sleeves, parallel to said shafts, to which the forks are rigidly connected, bearings in which said sleeves are slidably supported, a control lever disposed between the sleeves and substantially at right angles thereto, means for supporting one end 70 of the lever to enable the same to rotate or to swing toward one sleeve or the other, and means between the lever and sleeves for causing the latter to be moved in opposite directions longitudinally when the lever is rotated, and to be moved in a common direction longitudinally when the lever is swung toward one sleeve or the other.
8. A structure as in claim 2, in which said independent means comprises circular bearing means in which the shaft is turnably and eccentrically mounted, fixed journal means in which said circular bearing means are turnably mounted, and means applied to the circular bearing means for rotating the same in 75 its journal.
- In testimony whereof I affix my signature.
GEORGE W. WINDSOR.
